EYE GLASS HINGE UNIT

Edward J. Mankowski, 206 Parker Ave.,
Maplewood, N.J. 07040

Filed Aug. 9, 1967, Ser. No. 8,192

Term of patent 14 years

(Cl. D57—1)

FIG. 1

FIG. 2

FIG. 3

FIG. 4

FIG. 5

FIG. 6

FIG. 1 is a front perspective view of an eye glass hinge unit, showing my new design;

FIG. 2 is a perspective view of one of the hinge elements removed therefrom for purposes of illustration;

FIG. 3 is a perspective view of the other hinge element removed from the hinge unit for purposes of illustration;

FIG. 4 is a front elevational view of the hinge element shown in FIG. 2;

FIG. 5 is a side elevational view thereof, the opposite side thereto being a mirror image; and

FIG. 6 is a rear elevational view thereof.

I claim:

The ornamental design for an eye glass hinge unit, as shown and described.
